UNITED STATES PATENT OFFICE.

WALTER M. CROSS, OF KANSAS CITY, MISSOURI, ASSIGNOR TO GASOLINE PRODUCTS COMPANY, OF NEW YORK, N. Y., A CORPORATION OF NEW YORK.

APPARATUS FOR TREATING PETROLEUM OILS.

Application filed July 20, 1922. Serial No. 576,197.

To all whom it may concern:

Be it known that I, WALTER M. CROSS, a citizen of the United States, residing in the city of Kansas City, county of Jackson, and 5 State of Missouri, have invented certain new and useful Improvements in Apparatus for Treating Petroleum Oils, of which the following is a specification.

This invention relates to an apparatus for 10 treating petroleum oils and refers more particularly to an apparatus in which the oil is treated from a crude product to refined gasoline in separate stages.

Among the objects of the invention are to 15 provide an apparatus in which the oil is introduced in a crude state and after being fractionally distilled, the separate fractions are treated in stages to produce further conversion; to provide an apparatus in which 20 the relatively low boiling point distillates are refined and are redistilled to produce finished gasoline while the heavier and higher boiling point products are diverted from the primary distillation stage and directed to a 25 cracking still where they are subjected to conversion temperature under high pressures to produce a synthetic crude in which a rearrangement of the molecular bodies contained in the oil has taken place, and a product 30 from which the higher boiling point fractions may be very easily extracted.

The single figure is a diagrammatic side elevational view of the apparatus. Referring to the drawings, the raw crude oil contained in a storage tank 1 is supplied through 35 a line 2 controlled by valves 3 and 4 by pump 5 to the still 6 which is preferably mounted above a furnace 7 which is heated by gas burner 8. In this still the oil is distilled, the 40 vapors passing off through the line 9 controlled by the valve 10 to refluxing towers 11, 12 and 13 through which the vapors successively pass due to the connecting lines 14 and 15 controlled by valves 16 and 17 respectively.

It is understood that any number of refluxing or dephlegmating towers may be used according to the fractional separation that is desired.

50 The vapors from the final tower 13 pass over through the line 18 controlled by valve 19 to a condenser coil 20 mounted in the condenser box 21. This product contains to a large extent cuts such as crude benzine and 55 lighter distillates in the nature of gasoline.

These distillates are collected in the tank 22 and may be drawn off through the line 23 controlled by valve 24 and charged to the agitator 25 where they are subjected to refining action with acid introduced through 60 the line 26 controlled by the valve 27 and caustic soda charged through the line 28 regulated by the valve 29. An additional sweetener such as sodium plumbate is introduced through the line 30 controlled by valve 31. 65 The liquid in the agitator is thoroughly mixed and agitated by means of an air pipe 32 positioned in the bottom of the receptacle. The refined distillate from the agitator is drawn off through the line 33 regulated by 70 the valve 34 and is charged to steam still 36 in which is positioned the steam coil 37. Here the distillate is re-distilled, the vapors rising through the line 38 controlled by the valve 39 and condensed in the water condensing coil 40, after which they are collected as liquid distillate or finished gasoline in the receiving tank 41 from which the liquid distillate may be drawn off through a draw-off line 42 controlled by a valve 43. 80

The refluxed products from the towers 11 and 12 are passed through the cooling coils 44 and 45 mounted in the condenser box 21. These products are collected in the tank 46. The lighter reflux condensate separated out 85 in the tower 13 is passed through a separate coil 47 and collected in the tank 48. Valves 49, 50 and 51 are positioned in the separate connecting lines between the coils and the tanks to regulate the flow of condensate 90 therethrough.

In addition to the condensate collected from the refluxing tower 13 there is returned from the steam still through the line 52 controlled by the valve 53 the higher boiling 95 point distillates which do not pass over to the receiving tank at the temperatures maintained in the secondary or steam still stage of re-distillation.

The liquid products collected in the tanks 100 46 and 48 are drawn off through the lines 54 and 55 controlled by valves 56 and 57 and serve as charging stock to a cracking unit into which they are charged through the line 58. The cracking unit comprises a heating coil 59 mounted in a furnace 60 heated by gas burner 61, a reacting chamber 62 connected to the cracking coil by transfer line 63 controlled by valve 64 and a cooling coil 65 connected to the reacting chamber by a 110

pipe 66 in which is interposed a reducing valve 67. The cooling coil in turn is connected to gas separator 68 by line 69 controlled by valve 70 and has a liquid draw-off line 71 through which the synthetic crude produced in the cracking unit is returned to the storage tank 72 and a gas relief valve 73. The synthetic crude returned from the cracking unit is recycled with the incoming 10 crude oil through the still 6 being charged through the line 74 to the line 2 through which the crude is charged.

In operation the crude oil is distilled in the primary still and the vapors fractionated to produce separate distillates. The condensate collected in the tank 46 will consist principally of a higher boiling point product such as gas oil and oils of a similar nature while in the tank 48 will collect cuts 20 of the kerosene series, while in the final tank 22 lighter distillate such as crude benzine, naptha and the like will be collected. The lighter products such as those collected in the tank 22 as explained are refined in the 25 agitator 25 with acid, caustic soda, sodium plumbate and other refining means, and are then directed to a steam still as shown at 36 where the refined product is redistilled to refined gasoline which collects in the receiving tank 41, while the higher boiling point or objectionable cuts are drawn off from the still and returned to the tank 48 and there combined with the relatively 30 higher boiling point oils which are charged 35 with the gas oil like products from the tank 46 to the heating coil 59. In the cracking unit the oils comprising the gas oil and kerosene bottoms comprising the charging stock are subjected first to a conversion tempera- 40 ture at pressures in excess of 500 pounds, temperatures ranging from 600° to 900° F. are satisfactory to produce conversion.

The oil is then passed through a transfer line to the reacting or digesting chamber 45 where like pressure is maintained in order to permit the conversion to continue while the oil remains substantially in the liquid phase. The collection of the oil in this chamber in a considerable body at the temperature and pressures suggested permit a 50 digestion or stabilization of the heated oil which produces a re-arrangement of the molecular bodies to form what may be termed as a synthetic crude. From the reacting chamber 62 the oil is drawn off as 55 desired, and passed through the cooling coil 65 and thence through the gas separator 68 wherein the incondensable gas may be removed, while the liquid products are returned to the synthetic crude storage tank 60 and recycled through the system by being introduced with the charging stock to the still 6.

The character of the synthetic crude after 65 conversion in the cracking unit as explained,

is such that the lighter or lower boiling point fractions are easily extracted therefrom by simple distillation. The residual products unvaporized in the still 6 are drawn off through the line 76 controlled by 70 the valve 77 and passed through the cooling coil 78 after which they are collected in a tank 79. These residual products consist principally of such cuts as fuel oil and like 75 heavier residual carbon containing products which may be drawn off through the line 80, or if desired, directed through the line 81, controlled by the valve 82 and charged with the gas oil and kerosene bottoms through the line 58 to the cracking unit. 80

I claim as my invention:

1. In an apparatus for treating petroleum oils, the combination with means for fractionally distilling the oil having separate condensate collecting means, of means 85 for refining the lighter fractions of a gasoline-like character, a drawoff line for tarry residual products from the fractional distilling means and means whereby the tarry residual products are combined with the 90 higher boiling point fractions from said distilling means, a pressure distilling means for cracking said higher boiling point fractions and residual products from the fractional distilling means comprising a heating 95 element, a reaction chamber connected thereto whereby the higher boiling point fractions and residual products may be subjected to the converting reaction of temperatures and pressures regulated to produce conversion of the oil while in substantially liquid phase, means for returning the synthetic products from the cracking means to the initial distilling means for redistillation. 105

2. In an apparatus for treating petroleum oils, the combination with a fractional distilling means having separate reflux condensing means for simultaneously and separately extracting the condensates of a different boiling point, means for removing the tarry residual products from the fractional distilling means and connections for combining said products with the separate heavier refluxed condensates, refining and redistilling elements for retreating the lighter gasoline-like condensates, a cracking means for treating the combined heavier condensates and tarry products from the initial stage comprising a heating element, 110 a relatively larger reaction chamber connected thereto, control means for maintaining pressures to effect the cracking in the liquid phase, means for drawing off the cracked product and a return line for recharging the same to the fractional distilling means for redistillation. 120

3. In an apparatus for treating petroleum oils the combination with a primary distilling means of means for fractionating 130

and separately condensing and collecting the vapors evolved, means for removing the tarry residual products and combining them with the higher boiling point condensates, 5 refining and redistilling means connected to the low boiling point oil collecting means, means for cracking the higher boiling point condensates and tarry residual products comprising a heating coil and reacting chamber, whereby the oil is heated and subjected to a conversion action while being maintained by pressure in the liquid phase, means for controlling said pressure, of means for drawing off and cooling the converted oil and recycling it to be retreated 15 in the primary distilling zone.

WALTER M. CROSS.
